UNITED STATES PATENT OFFICE.

JOHN C. TAYLOR, OF FINDLAY, OHIO.

CAR-COUPING.

1,098,135.

Specification of Letters Patent. Patented May 26, 1914.

Application filed November 13, 1913. Serial No. 800,849.

To all whom it may concern:

Be it known that I, JOHN C. TAYLOR, a citizen of the United States, residing at Findlay, in the county of Hancock and State of Ohio, have invented certain new and useful Improvements in Car-Couplings, of which the following is a specification, reference being had therein to the accompanying drawing.

10 My invention relates to improvements in car-couplings.

The object of my invention is to provide a car-coupling of the Janney type in which the knuckle will by gravity automatically swing outwardly after the lock for holding the same has been released.

15 Another object of my invention is to so provide the knuckle that it can be readily removed and inserted, whereby the assembling of the several parts in the manufacture of the coupling is readily accomplished.

20 A further object of my invention is to provide a lock which will more securely hold the knuckle in its inward position and at the same time providing a simple construction and operation, and also providing means whereby the parts are readily assembled.

25 A still further object of my invention is to provide a simple, cheap and effective coupling of this character having certain details of structure hereinafter more fully set forth.

In the accompanying drawings: Figure 1 is a top plan view of a coupling embodying 30 my invention showing the draw-head partly broken away to show the knuckle and the locking latch. Fig. 2 is a perspective view 35 of the coupling showing the knuckle removed and showing the draw-head in horizontal section. Fig. 2a is a perspective view 40 of the knuckle. Fig. 3 is a vertical sectional view taken on the line 3—3 of Fig. 1. Fig. 4 is a vertical sectional view similar to Fig. 3 of the modified form of pivotally mounting 45 the knuckle. Fig. 5 is a perspective view of the locking latch.

Referring now to the drawings, 1 represents the draw-head which is of the ordinary Janney type exterior contour and needs 50 no further description. The draw-head, as shown in Figs. 1 and 2, is of a hollow form and provided at its lower end with an obliquely arranged slot 2, having the obliquely

arranged slanting flanges 3, upon which rest the locking latch 4. This slot 2, as shown, 55 is arranged directly in the center of the draw-head and the latch 4 is adapted to lock the knuckle in its inward position, as will be hereinafter more fully described. The draw-head at one side is provided at its 60 upper and lower edges with the outwardly extending horns 5 and 6, between which the knuckle 7 is pivoted. The ears 5 and 6 are provided with vertical openings 7 and 8 through which the pin 9 passes. This pin 65 also passes through an opening 10 in the knuckle and whereby the knuckle is pivotally mounted between the ears 5 and 6. The horn 6 surrounding the opening 8, is provided with an upwardly extending sleeve 11, which 70 has a worm 12 on its exterior. Said worm extends only partially around thereof, as shown in Fig. 2 of the drawings. The knuckle 7 is provided with a cylindrical portion 11, which has its lower end provided with a 75 circular recess 12' having one side cut away, as indicated at 13, which allows the knuckle to be readily inserted between the ears 5 and 6, and also allows the sleeve 11 to pass within the circular opening 12. The opening 12 is provided with a worm groove 14 adapted to receive the worm carried by the sleeve 11, for the purpose, all of which will be hereinafter more fully described.

The sleeve 11 and its worm not only serves 85 as a means for causing the knuckle to swing outwardly, but also serves as an additional bearing for the knuckle to work upon, as clearly shown in Fig. 3 of the drawing. The bolt 9, as heretofore described, passes 90 downwardly through the horns 5 and 6 and through the opening 10 in the cylindrical portion 11 of the knuckle, and serves as a pivot upon which the knuckle swings. A cotter pin 15 is employed to prevent the upward movement of the bolt 9, although any other well-known locking means could be employed to prevent this upward movement of the bolt.

The portion 16 of the knuckle is that 100 which extends across the draw-head and forms the coupling interlocking with a similar coupling carried by the other car. The portion 17, when the knuckle is in its coupled position, passes inwardly into the hollow 105 draw-head and the locking latch 4, moves

downwardly beyond the same and is engaged by the portion 17, whereby the knuckle is prevented from swinging outwardly.

The locking latch 4 is of a solid triangular form having at its side the curved portions 17 which rest upon the inclined flanges 3 of the draw-head, and whereby it is free to slide thereon. The center of the locking lever 4 is provided with a downwardly extending flange 18, which is adapted to fit between the flanges 3 and whereby it is prevented from twisting in the draw-head and yet have a free movement up and down within the slot 2. The upper edge of the locking latch 15 is provided with an ear 18, through which passes a cable 19, which passes upwardly and outwardly through an opening in the upper end of the draw-head, whereby the locking latch may be drawn upwardly in the slot 2, 20 to bring it in rear of the arms 17 of the knuckle so that the knuckle is free to swing outwardly.

The knuckle, as shown, is of very heavy form and made of metal and when the latch 25 is drawn upwardly so that the arm 17 is not engaged thereby, the same will swing outwardly along the worm 12, of the sleeve 11 and automatically opened. It being understood that when the knuckle is swung inwardly in its coupling position, it is raised by the worm engaging groove 14 and the minute the lock 4 is drawn rearwardly away 30 from the arm 17, the knuckle by gravity swings outwardly.

35 In Fig. 4, instead of having the bolt 9, extend all the way through the knuckle, the knuckle is simply provided with a recess 21, into which a pin 22 extends, the pin 22 being secured in the ear 5, by means of a transverse pin 23. In this form it will be seen that the pin 22 forms the pivot at the upper 40 end and the sleeve or extension 24 forms the pivot at the lower end. In this form the cylindrical portion 11 of the knuckle is cut away, as indicated at 13, in precisely the same manner and is provided with the worm 45 connection for causing the knuckle to swing outwardly, as heretofore described.

While I have shown and described this 50 specific form of locking latch and knuckle, it will be seen that this could be varied without departing from my invention.

Having thus described my invention, what I claim and desire to secure by Letters Patent is:

55 1. A car coupling comprising a hollow draw-head having ears at its upper and lower edges adjacent one side, one of said ears having an upwardly extending lug provided with a worm, a knuckle between the 60 said ears and having a recess to receive the upwardly extending member and having a worm groove to receive the worm, whereby the knuckle will swing outwardly by gravity, and means for locking the knuckle in its 65 inward position, substantially as shown.

2. A car-coupling comprising a hollow draw-head, ears extending from the upper and lower edges adjacent one side, the lower ear having an upwardly extending member 70 provided with a worm around a portion thereof, a knuckle fitting between the ears and having a recess in its lower edge provided with a cut-away portion to allow the upwardly extending member to enter the 75 same and said recess having a worm groove to receive the worm of the said member, whereby the knuckle is raised when moved inwardly and a sliding locking latch within the draw-head for locking the knuckle in its 80 inward position.

3. A car coupling comprising a hollow draw-head having horns at its upper and lower edges adjacent one side, the lower horn having an upwardly extending sleeve having 85 a worm on a portion thereof, a knuckle having a cylindrical portion between the horns, the lower end of the cylindrical portion having a vertical recess having one side cut away to allow the sleeve of the lower horn 90 to pass therein and the said vertical recess having a worm groove to receive the worm of the sleeve, a pin passing downwardly through the harness and the cylindrical portion of the knuckle, and a latch adapted to 95 lock the knuckle in its inwardly raised position.

In testimony whereof I hereunto affix my signature in the presence of two witnesses.

JOHN C. TAYLOR.
